Primary Examiner—T. Chase Nelson*Assistant Examiner*—Karen Acker*(74) Attorney, Agent, or Firm*—Dickstein Shapiro LLP(57) **CLAIM**

The ornamental design for a mini wire tray, as shown and described.

DESCRIPTION

FIG. 1 is a first end view of the mini wire tray of the present invention;

FIG. 2 is a second end view of the mini wire tray of the present invention;

FIG. 3 is a first side view of the mini wire tray of the present invention;

FIG. 4 is a second side view of the mini wire tray of the present invention;

FIG. 5 is a front view of the mini wire tray of the present invention;

FIG. 6 is a back view of the mini wire tray of the present invention; and,

FIG. 7 is a perspective view of the mini wire tray of the present invention.

The break lines dividing a section of the mini wire tray indicate that no particular length is claimed.
